F. E. WELLMAN AND F. H. SIBLEY,
SYSTEM FOR TREATING HYDROCARBON OILS,
APPLICATION FILED OCT. 19, 1916.

1,335,770.

Patented Apr. 6, 1920.

UNITED STATES PATENT OFFICE.

FRANK E. WELLMAN AND FREDERICK H. SIBLEY, OF KANSAS CITY, KANSAS,
ASSIGNORS TO THE KANSAS CITY GASOLINE COMPANY, OF KANSAS CITY,
KANSAS, A CORPORATION OF KANSAS.

SYSTEM FOR TREATING HYDROCARBON OILS.

1,335,770.

Specification of Letters Patent.

Patented Apr. 6, 1920.

Application filed October 19, 1916. Serial No. 126,629.

To all whom it may concern:

Be it known that we, FRANK E. WELLMAN and FREDERICK H. SIBLEY, citizens of the United States, residing at Kansas City, in 5 the county of Wyandotte and State of Kansas, have invented certain new and useful Improvements in Systems for Treating Hydrocarbon Oils, of which the following is a specification, reference being had therein to 10 the accompanying drawing.

This invention relates to a system for cracking hydrocarbons in which superheated steam is used as the agency for conveying and imparting the necessary heat to the 15 cracking coil or still containing the oil in either liquid or vapor form.

Our invention has for its object to effect a certain economy on fuel and efficiency in 20 operation by using the exhaust steam from the cracking coil chamber for heating or vaporizing or both, the feed water in the boiler. Ancillary features will appear from the specific description hereinafter.

We attain our object by using a steam 25 boiler to receive and vaporize the feed water, a superheater to receive the steam from the boiler and raise the temperature to the desired point, a steam jacket or shell around the cracking coil taking its steam 30 from the preheater and exhausting through a suitable pipe line into the heating tubes of the boiler, which in turn exhaust through a steam trap from which the water of condensation may be taken up by the boiler 35 feed pump and mingled with the cold feed water supplied to the boiler.

A furnace, indicated by an oil nozzle 11^a, or other auxiliary heating means should be provided for the boiler, but ordinarily this 40 should not be necessary during operation, as the temperature of the exhaust steam from the cracking coil chamber would be not less than 600 degrees F.

In the accompanying drawing, 45 Figure 1 is a diagram showing the arrangement of the system.

Fig. 2 shows a modified form of the boiler.

Fig. 3 is a sectional view of the boiler in 50 Fig. 2.

Referring to the drawings, 1 is a cracking coil inclosed in the shell 2. 3 is a pump for pumping liquid or gaseous oil into the cracking coil. 4 is a steam pipe leading

from the cracking coil chamber to the coil 5 which is surrounded with the water to be vaporized. 6 is the exit tube of coil 5. 7 is a steam trap. 8 is a water pipe for conducting condensed water from the steam trap to the receiving side of the feed water pump. 9 is the water supply pipe line. 10 is the feed water pump for supplying water to the boiler 11. 12 is a steam pipe to conduct steam from the boiler 11 to the superheater coil 13. 14 is the steam superheated furnace of any desirable construction. 15 is a steam pipe for conducting highly superheated steam into the cracking coil chamber 2. The boiler shown in Fig. 2 may be used. In this, 16 is a steam drum for receiving the hot steam from pipe 4. 17 is a system of tubes under the water in the boiler through which the hot steam passes to drum 18 having exit tube 6 for conducting the excess steam and condensed water 75 to the steam trap 7.

The method of operation is as follows:

The hydrocarbon to be treated is forced by pump 3 into the cracking coil 1. Suitable cracking temperature is maintained in 80 the coil by means of the highly superheated steam surrounding the coil in the chamber 2. The cracked hydrocarbons then pass to a suitable cooling apparatus through pipe 20, which has a valve inserted therein for the 85 purpose of maintaining pressure.

The highly superheated steam passes from the cracking coil chamber through pipe 4 to the coil 5 where it imparts most of its heat to the water in boiler 11 and so 90 vaporizes the water. The steam and condensed water from coil 5 pass out the pipe 6 to the steam trap 7. The warm water of condensation passes from the steam trap 7 by means of pipe 8 to the receiving side of 95 pump 10 and is pumped into the boiler which may have a steam pressure of about 10 pounds per square inch. In the boiler 11 the water comes in contact with the hot steam coil 5 and is raised to its boiling point 100 at the pressure employed. The steam thus formed passes by means of pipe 12 to the super-heater coil 13. Here it is heated to cracking temperature by means of heat derived from the furnace 14, or equivalent 105 agency, which may be of any convenient type. This super-heated steam then passes through pipe 15 into the chamber space around

the cracking coil 1. Here the steam supplies the proper heat for cracking the oil and passes out through pipe 4 into coil 5 to give up the remainder of its heat to the water in the boiler to vaporize the same.

In case the boiler shown in Figs. 2 and 3 is used, the hot steam from 2 passes through pipe 4 into the drum or head 16 and thence into the tubes 17 situated under the water 10 in the boiler to be vaporized. While passing through tubes 17 the steam imparts its heat to the water and passes partly condensed into the drum or head 18 from which the excess steam and condensed warm water 15 pass through pipe 6 to the steam trap 7.

It will be understood that the drawing and description herewith presented of the cracking coil, pump or compressor, and pipe line for the oil to be cracked, are rudimentary and merely suggestive as to the apparatus actually required to practise the invention. Those skilled in the art, however, can supply the necessary elements, such as valves, condensing means, supply and receiving tanks, etc., and it is to be understood that these elements are implied, and are omitted merely in the interest of simplicity and clarity. For example, it is very necessary to provide precooling means, and 30 a pressure retaining valve at the discharge end of the still pipe 20, but such elements in themselves form no part of the present invention.

Having thus described our invention what 35 we claim and desire to secure by Letters Patent in the United States is:—

1. In a system for treating hydrocarbon oils, a cracking still, a steam chamber for heating said still, means for passing the 40 hydrocarbons under suitable cracking pressure through said still, a water boiler or vaporizer, a superheater, external means for supplying heat to said superheater, pipe connections from said boiler to said superheater, and from the latter to the steam chamber of the still, means for conducting the exhaust superheated steam from the still heating chamber into contiguity with the water in the boiler, and means to force the 45 water and steam from the boiler to the superheater, to maintain the circulation in the entire heating system.

2. In a system for treating hydrocarbon oils, a cracking still, a steam chamber for 50 heating said still, means for passing the water and steam from the boiler to the superheater, to maintain the circulation in the entire heating system.

hydrocarbons under suitable cracking pressure through said still, a water boiler or vaporizer, a superheater, external means for supplying heat to said superheater, pipe connections from said boiler to said superheater, and from the latter to the steam chamber of the still, a coil in said boiler, a pipe connection for exhaust steam from the still heating chamber to said coil, to heat the water in the boiler, and a pump 60 connected between the boiler and the exhaust end of the coil within it, said pump acting to force a circulation of water and steam through the system.

3. In a system for treating hydrocarbon 70 oils, a cracking still, a steam chamber for heating said still, means for passing the hydrocarbons under suitable cracking pressure through said still, a water boiler or vaporizer, a superheater, external means for 75 supplying heat to said superheater, pipe connections from said boiler to said superheater, and from the latter to the steam chamber of the still, a coil in said boiler, a pipe connection for exhaust steam from the 80 still heating chamber to said coil, to heat the water in the boiler, together with a discharge connection from said heating coil, a steam trap connected thereto, and a pump connected between the boiler and the exhaust end of the coil within it, said pump 85 acting to force a circulation of water and steam through the system.

4. In a system for treating hydrocarbon 90 oils, a cracking still, a steam chamber for heating said still, means for passing the hydrocarbons under suitable cracking pressure through said still, a water boiler or vaporizer, a superheater, external means for 95 supplying heat to said superheater, pipe connections from said boiler to said superheater, and from the latter to the steam chamber of the still, a coil in said boiler, and a pipe connection for exhaust steam from the still heating chamber to said coil, 100 to heat the water in the boiler, together with discharge connections for said coil, and pressure means to return warm water due to condensation therein, to the boiler, to assist in raising the temperature of the 105 feed water supplied thereto.

In testimony whereof we affix our signatures.

FRANK E. WELLMAN.
FREDERICK H. SIBLEY.
